(57) **CLAIM**

The ornamental design for luggage with wheels and raised rails, as shown and described.

DESCRIPTION

FIG. 1 is a perspective view of the raised rails for the outer surface of luggage;

FIG. 2 is a front elevation view thereof;

FIG. 3 is a left elevation view thereof;

FIG. 4 is a right elevation view thereof;

FIG. 5 is a top plan view thereof; and,

FIG. 6 is a bottom plan view thereof.

The broken line showing of a suitcase and portions thereof is included for the purpose of illustrating environment and forms no part of the claimed design.
